UNITED STATES PATENT OFFICE.

DAVID H. GOBIN, OF SPRINGFIELD, ILLINOIS.

IMPROVEMENT IN CHURNS.

Specification forming part of Letters Patent No. 129,471, dated July 16, 1872.

Specification describing a new and useful Improvement in Churning-Machine, invented by DAVID H. GOBIN, of Springfield, in the county of Sangamon and State of Illinois.

Figure 1 is a detail vertical section of my improved churning-machine. Fig. 2 is a detail perspective view of the air-pumps and its detaching lever.

Similar letters of reference indicate corresponding parts.

My invention has for its object to furnish an improved churning-machine, simple in construction and convenient in use.

A is a bed-plate from which rise the posts B. The two posts upon each side meet at an angle, and to their upper ends are attached bearings C for the journals of the shaft D. E is the churn-body provided with a cover, F. In the bottom of the churn E is placed a screen, G, made of perforated sheet-metal, and to the edges of which is attached a light frame, H. To the opposite side-bars of the frame H are attached the lower ends of two bars, I, which pass up along the inner surfaces of the churn-body E, and the upper ends of which project through holes in the cover F. J is the dasher having handle K. To the upper ends of the two parts of the dasher-handle K are pivoted the lower ends of the two connecting-rods L,

the upper ends of which are pivoted to two cranks, M. N is the barrel of an air-pump the lower end of which enters the churn through a hole in the cover F. The upper end of the piston-rod O of the barrel N is pivoted to the lower end of the connecting-rod P, the upper end of which is pivoted to the short crank Q formed upon the shaft D, so that the air-pump may be operated to force air into the churn by the revolution of the shaft D. The barrel N is connected with and supported by a lever, R, one end of which is pivoted to one of the posts B, and its other is secured to another of said posts by a pin. The lever R enables the air-pump to be disconnected from the churn when desired. To one end of the shaft D is attached the crank S, by means of which the machine is operated.

Having thus described my invention, I claim as new and desire to secure by Letters Patent—

The combination of the pivoted-lever R with the pump-barrel N, piston-rod O and connecting-rod P, substantially as herein shown and described, and for the purpose set forth.

DAVID H. GOBIN.
